CHARLES A. MOSGROVE, OF WATERBURY, CONNECTICUT, ASSIGNOR TO THE AUTOYRE COMPANY, OF OAKVILLE, CONNECTICUT, A CORPORATION OF CONNECTICUT

SLIDE BUCKLE

Application filed May 22, 1929. Serial No. 364,967.

This invention relates to a slide buckle such as is used on suspenders and the like, particularly for use on shoulder straps of overalls, and has for an object to provide a buckle of this type in which there are no rolled eyes to rub against the shirt or other garments of the wearer, cut the garment or cause discomfort to the wearer. It is also an object of the invention to provide a buckle which may be applied either side up, thus making it simpler to apply and increasing production of garments. Another object of the invention is to provide a buckle which will lie perfectly flat, does not require welding or similar operations and which can be made on an automatic machine, and therefore, can be made cheaper than some of the two piece slides now on the market. It is still another object of the invention to provide a slide of this character which will have a firmer grip on the strap and therefore will be less likely to slip under strain.

With the foregoing and other objects in view, the invention consists in certain novel features of construction and arrangements of parts as will more fully disclosed in connection with the accompanying drawings.

In these drawings

Fig. 1 is a side elevation of the buckle showing my improved construction and with the central clip in section.

Fig. 2 is a transverse section substantially on line 2—2 of Fig. 1.

Fig. 3 is a view similar to Fig. 1 showing a slightly modified construction.

Fig. 4 is a transverse section substantially on line 4—4 of Fig. 3.

Fig. 5 is a side elevation of a still further modification.

Fig. 6 is a transverse section substantially on line 6—6 of Fig. 5.

Fig. 7 is a side elevation of another modification.

Fig. 8 is a transverse section substantially on line 8—8 of Fig. 7.

Fig. 9 is an edge view of the buckle shown in Fig. 7.

Fig. 10 is a side elevation of a still further modification.

Fig. 11 is a transverse section substantially on line 11—11 of Fig. 10.

Fig. 12 is a side elevation of still another modification, and

Fig. 13 is a transverse section substantially on line 13—13 of Fig. 12.

Referring to the drawings it will be seen that all of the modifications shown are of the same general construction, the modifications showing changes only in the shape of the outer side bars of the buckle. Referring to Figs. 1 and 2 it will be seen that the buckle is made in one piece of wire folded upon itself at its midlength as shown at 14 and extending side by side to form a portion 15 of a central bar. The two portions of wire are then extended outwardly in opposite directions to form end bars 16 and then extend parallel with the central bar 15 and spaced laterally therefrom to form side bars 17. They then extend inwardly toward each other to provide end bars 18 and then side by side as shown at 19 to provide a second center bar portion in alignment with the central bar portion 15. The free ends of the bars 19 are connected together and to the central bar portion 15 by a tubular metal clip 20 which may be a strip of sheet metal wrapped around the elements as shown. This clip rigidly secures the ends of the bars 19 together as well as the two portions of the central bar, and makes a very rigid construction without the necessity of any welding or similar operations. The wire shown in the drawings is either square or rectangular in cross-section, but obviously could be made of wire of either circular or other suitable shape. The square or rectangular wire is preferred as the edges give a better grip on the material of the strap so that the buckle is less likely to slip under load. The surface of the wire may be smooth or it may be knurled as indicated by the lining on the drawings. The knurling also increases the grip on the strap.

Referring to Figs. 3 and 4 this buckle is the same as is shown in Figs. 1 and 2, except that the side bars 21 are flattened at their central portions as indicated at 22. This flattening decreases the width of the two loops formed

between the central bar and the side bars at the central portion of the buckle while giving the full widths of the loops at their opposite ends as shown at 23 to take care of any 5 seams there might be in the straps.

The form shown in Figs. 5 and 6 is the same as shown in Figs. 3 and 4 except that the side bars are flattened throughout substantially their entire lengths as shown at 24 10 instead of only at the central portion as shown in Fig. 3.

In Figs. 7, 8 and 9 the buckle is formed the same as shown in Figs. 1 and 2, then the side bars 17 are humped adjacent their opposite 15 ends as shown at 25 to put a bend in the strap and still further reduce the liability to slip. This bend increases the angle of the strap about the bars as the strap passes through the buckle and therefore, increases the holding 20 effect.

In the form shown in Figs. 10 and 11 the side bars are swedged adjacent their outer edges as indicated at 26 to thus reduce the thickness of the bars and increase their 25 width, but leaving their inner edges 27 of substantially the full thickness of the wire. This makes a bar which is very rigid in both directions and which also has a very firm grip on the strap as the holding edge of the 30 wire remains the full size. This inner edge, and in fact the entire surface of the wire, may be knurled if desired at the time of swedging. This construction improves the appearance of the buckle and gives a stronger frame with a smaller wire than would a mere flattening of the full width of the wire. 35

In Figs. 12 and 13 the side bars are provided with a series of flattened surfaces 28 leaving a series of notches 29 and 30 in its 40 opposite side edges giving a sort of sawtooth effect, which gives a very firm hold on the material of the strap. The flat surfaces may also be left with small projections 31 which engage the surface of the material of the strap and 45 still further increase the holding effect. These projections or lugs 31 may also be used on the flat surfaces of the forms of Figs. 3 and 5.

It will, of course, be understood that while 50 only the surfaces of the buckle of Figs. 1 and 2 are shown knurled, the surfaces of the other forms may be knurled if desired. These buckles may be formed entirely automatically, and have great strength without 55 the necessity of welding or any other similar operations. It also will be apparent they have no eyes to rub on a shirt, to cut it, or to give discomfort to the wearer. There is no separate slide on the buckle to interfere with the 60 attaching of the buckle to a suspender, thus making it quicker and easier to handle, and it will work equally well either side up, and therefore, may be applied in this way.

Having thus set forth the nature of my 65 invention, what I claim is:

1. A slide buckle comprising a piece of wire folded upon itself at its midlength to form a portion of a central bar, the two side portions of the wire then extending in opposite directions from said central bar to form 70 end bars and then substantially parallel to the central bar on opposite sides thereof to form the side bars of the buckle, said side bars being swedged to provide a plurality of flat faces separated by notches at the ends of said faces at each edge of the bars and projections between the notches, the sides being then turned inwardly toward each other to form the opposite end bars and then inwardly toward the free end of the first central bar to form another portion in alignment therewith, and means for connecting together the free ends of the two portions of the central bar. 75

2. A slide buckle comprising a single piece 80 of wire of a cross section which provides substantially plane side surfaces with a relatively sharp edge between adjacent surfaces, said wire being folded upon itself to form a portion of a central bar and then extending 85 outwardly in opposite directions therefrom and substantially parallel to the central bar to form loops on opposite sides thereof, the free ends of the wire extending inwardly side by side from the opposite end of the buckle 90 toward the free end of the first portion of its central bar to form another portion of the central bar in alignment therewith, and a sleeve extending substantially less than the full length of the central bar and embracing 95 the inner opposed ends of the end portions of the central bar to secure them together and said sleeve being of greater diameter than the central bar whereby to enlarge the central bar intermediate its ends and to allow 100 at the ends of the sleeve for the seams of a strap. 105

3. A slide buckle comprising a piece of substantially rectangular wire folded upon itself at its midlength to form a portion of a central bar, the two side portions of the wire then extending in opposite directions from 110 said central bar to form end bars and then substantially parallel to the central bar on opposite sides thereof to form the side bars of the buckle, said side bars being swedged to decrease their thickness and increase their 115 width, the sides being then turned inwardly toward each other to form the opposite end bars and then inwardly toward the free end of the first central bar to form another portion in alignment therewith, and a sleeve embracing the opposed inner ends of the two portions of the central bar to secure them together. 120

4. A slide buckle comprising a single piece of wire folded upon itself to form a portion of a central bar and then extending outwardly in opposite directions therefrom and substantially parallel to the central bar to form 125

loops on opposite sides thereof to form the side bars of the buckle, the central portions of said side bars, being swedged whereby to decease their thickness and increase their width, the free ends of the wire, extending inwardly side by side from the opposite end of the buckle toward the free end of the first portion of the central bar to form another portion of the central bar in alignment therewith, and a sleeve extending substantially less than the full length of the central bar and the swedged portions of the side bars and embracing the inner opposed ends of the portions of the central bar to secure them together.

5 5. A slide buckle comprising a single piece of a substantially rectangular wire folded upon itself to form a portion of a central bar and then extending outwardly in opposite directions therefrom and substantially parallel to the central bar to form loops on opposite sides thereof, the outer bar of the loop being swedged at its outer edge to reduce the thickness of this edge and increase the width 20 of the bar leaving the inner edge of the bar of substantially its original thickness, the free ends of said bars extending inwardly side by side toward the free end of the central bar portion to provide another portion in 25 alignment therewith.

6. A slide buckle comprising a central bar portion extending longitudinally and a pair of rectangular side bars spaced laterally therefrom on opposite sides thereof and connected to the central bar portion at their ends to form loops, said side bars being swedged at their outer edges to reduce the thickness of the outer edge of the bar and increase its width leaving the inner edge of the bar of 30 substantially its full thickness.

7. A slide buckle comprising a wire forming a central bar and side bars spaced therefrom on opposite sides thereof, and connected to the central bar portion at their ends to 35 form loops, said side bars being swedged at their outer edges to reduce the thickness of the outer edges of the bars and leaving the inner edges of the bars of substantially their full thickness.

50 50. In testimony whereof I affix my signature.
CHARLES A. MOSGROVE.
